UNITED STATES PATENT OFFICE

94,761

DESIGN FOR A RADIATING ELEMENT FOR GAS HEATERS

Hubert R. Humphrey, Kalamazoo, Mich., assignor
to General Gas Light Company, Kalamazoo,
Mich.

Application November 12, 1934, Serial No. 53,984

Term of patent 7 years

To all whom it may concern:

Be it known that I, Hubert R. Humphrey, a citizen of the United States, residing in the city and county of Kalamazoo, State of Michigan, have invented a new, original, and ornamental Design for Radiating Element for Gas Heaters, of which the following is a specification, reference being had to the accompanying drawing, forming part thereof, in which:

Fig. 1 is a front elevational view, and
Fig. 2 is a side elevational view of a radiating element for gas heaters, showing my new design.

I claim:

The ornamental design for a radiating element for gas heaters, as shown.

HUBERT R. HUMPHREY.
